UNITED STATES PATENT OFFICE.

JOHN M. HARTMAN, OF PHILADELPHIA, PENNSYLVANIA.

VALVE.

SPECIFICATION forming part of Letters Patent No. 327,548, dated October 6, 1885.

Application filed August 22, 1884. Serial No. 141,217. (No model.)

To all whom it may concern:

Be it known that I, JOHN M. HARTMAN, of the city and county of Philadelphia, in the State of Pennsylvania, have invented certain 5 new and useful Improvements in Gas and Hot-Blast Valves for Regenerative Stoves.

The following is a specification of my said improvements, reference being had to the accompanying drawings, wherein Figure 1 is a 10 top or plan view of the apparatus, the fire-brick lining of the upper portion being removed so as to show the valve itself. Fig. 2 is a view, partly in vertical section, on the line $x-x$ of Fig. 1, and partly in side elevation. 15 Fig. 3 is an end view of the valve-gland. Fig. 4 is a vertical central section thereof on the line $y-y$ of Fig. 3. Figs. 5 and 6 are respectively transverse and longitudinal sections through the valve-stem; and Fig. 7 is a section through one of the attachments by which 20 the packing-ring is secured and adjusted, the scale of the five figures last mentioned being much enlarged.

The principal features of my invention consist in combining, with the gas-connections, a 25 pair of valves having an intermediate escape, whereby any gas that leaks past the first valve is discharged into the open air; in a new manner of forming the valve-body and securing 30 the valve-seat thereto; in hinging the cap of the valve so that it may be swung around horizontally; in inclining the interior of the valve-disk to prevent accumulation of steam, and providing an exterior shield for the edge 35 of the disk; in a new manner of constructing the valve-stem so as to secure its free operation, and in rendering the packing and gland readily adjustable.

The valve casing or body is formed in two 40 sections similar in construction, and joined together, so as to form a continuous shell of substantially cylindrical form. These sections consist of cylindrical wrought-iron cases a a' , lined with fire-brick ff' , and having at top 45 and bottom annular flanged pieces c c' d d' , respectively, attached around the inner periphery of the cases a a' . The sections are joined together by uniting the bottom flange, d , of one to the top flange, c' , of the other, the 50 two remaining flanged pieces, c d' , serving to mount the apparatus upon the stove, &c.,

where it is to be used. The valve-seats b b' consist of hollow steel or wrought-iron rings attached to the bottom pieces, d d' , respectively, and having connections b^2 b^3 , for maintaining a water-circulation within. The fire-brick linings ff' are cut away or open around the upper surface of the rings b b' , leaving room for the valves to close upon their seats, as shown in Fig. 2, and lateral openings o o' 60 lead from these open spaces above the valve-seats to the outside air. These passages o o' are controlled by doors p p' , the upper of which is provided with a weighted arm, p^2 , while the lower one, p' , is not weighted, and 65 therefore will open with a slight pressure. These openings afford access to the valve-seats and end of the valve-disks for the purpose of cleaning them, and the lower door also serves as an escape for leakage, as will be presently 70 described.

The valves q q' are moved in a horizontal direction by their respective stems s s' , lateral recesses or compartments, consisting of caps j j' and nozzles k k' , being provided to permit 75 their withdrawal from their seats.

As the connections and actuating devices of the valves are similar throughout, it is only considered necessary in the remaining portions of this specification to describe a single 80 valve.

The purpose of combining a pair of valves and escape, as above specified, is as follows: In the operation of hot-blast apparatus the gas passing an open valve has a tendency to 85 leave a deposit on its face, which prevents it from shutting tight, and when blast is put in the stove it leaks through into the gas below the valve; this gas, igniting, burns the valve and destroys the lining of the gas-flues. 90

In my improved valve it will be seen that the lower door, p' , is held shut with a slight pressure only. Any blast now leaking past the first valve will blow open the door p' and escape to the air, instead of passing down and 95 burning the gas below.

I will now proceed to describe the construction of the valve and its operating device.

Heretofore valve-disks have been usually made with parallel faces—a form which traps 100 the steam from the water-circulation within them and causes them to crack and leak. I

therefore make the back r of the disk with an incline, as shown in Fig. 2, so that the least depth is at the end or side farthest from the valve-stem s . It is also provided on the outside with a hollow end shield, s^2 , so applied as to leave an air-space around a portion of its periphery. The purpose of this shield is to protect the end of the valve when open against the heat of the passing gas.

The cap k and nozzle j , forming the compartment for the withdrawal of the valve, are hinged to one another at l , and provided with bolts and nuts along their adjacent flanges to secure them when close together. A raised bearing-surface, f^2 , extends longitudinally through the cap and nozzle immediately beneath the valve-stem and parallel thereto. The valve-stem s , to which the valve is attached, is of tubular form and provided with pipes $t t'$, for maintaining a water-circulation throughout its interior, as well as that of the valve. Near the junction of the stem and valve I provide, on the under side thereof, two projecting bearings, g , adapted to rest and slide freely upon the bearing-surface f^2 of the cap and nozzle.

The projection of the bearing-surfaces g is sufficient to prevent the valve-disk when withdrawn into the cap from coming in contact with the bottom thereof, and thus the wear of the valve-face which is incident to bearings heretofore used is prevented.

Downwardly-depending guides h' (see Fig. 5) embrace the sides of the raised bearing-surface f^2 and prevent the lateral displacement of the stem. The stem is actuated by means of a pinion, w , engaging with teeth $v v'$, cast in the cylindrical periphery of the stem, and a stop, g^2 , is rigidly secured to the end of the stem in such a position as to abut against the bracket w' , that supports the pinion w , as soon as the valve is home upon its seat.

Heretofore it has been customary to place a stop inside of the valve-body for the valve-disk to strike against and indicate when it was shut. The dust collecting on this stop prevented the valve from closing more properly indicating its position, both of which defects are remedied by my improved arrangement of the stop above described.

The teeth v extend along the valve-stem s a sufficient distance to permit the withdrawal of the disk within the cap. If, then, access to the interior is desired, the bolts which secure the cap and nozzle are detached, and the cap and disk are opened out by swinging them horizontally upon the pivot l .

Heretofore, so far as I am aware, the glands of horizontal valve-stems have had no positive means of lateral adjustment, which, however, is necessary to properly compensate for the wearing down of the valve-disk or the springing of the stem and body by the effects of heat. To obtain such adjustment, I construct the gland r' with two horizontally-projecting eyes, $l' l'$, through which pass the screw-studs $i' i'$, by which the gland is attached to the end of the

cap. The sleeve u of the gland is in external diameter considerably smaller than the internal diameter of the opening in the end of the cap into which said sleeve extends. The openings of said eyes are much larger than the diameter of the studs, thus allowing a considerable amount of play. Adjacent to these eyes I mount upon the gland inclined set-screws $m' m'$, bearing upon the studs $i' i'$, and by the individual or combined movement of these set-screws a great range of adjustment of the gland can be obtained.

To prevent the stem from jamming in the sleeve u of the gland, the size of the opening therein is made throughout the upper half of its periphery slightly larger than the diameter of the stem, so that the stem bears only upon the bottom portion of the sleeve. This enlargement is indicated by the lines between m and n in Fig. 3.

It has been usual heretofore to pack glands for these valves with a ring set up by set-screws o' —a method which makes the packing too rigid and renders the stem liable to jam in the gland when the flue-dust settles on it. I therefore make the packing-ring in several segments, $n' n'$, lapping one another, with some play between their ends, as shown in Fig. 4. These segments are retained within an annular recess, g' , in the gland r' by means of a screw-gasket, n^2 . In the periphery of the gland are radial set-screws $o' o'$, whose inwardly-projecting ends are surrounded by coiled springs e , (see Fig. 7,) which bear upon each segment of the packing-ring. By the adjustment of the set-screws o' the segments can be separately set up into proper contact with the valve-stem, the elasticity of the spring permitting the packing to yield somewhat, and thus preventing any tendency to jam.

As the ends of the teeth $v v'$ in the stem have the same cylindrical contour as the main portion of the stem itself, they pass freely through the packing-ring n' , and the width of the ring being greater than the distance between two teeth a close joint is always maintained between the packing-ring and the toothed portion of the stem.

The lower valve, q' , is similarly constructed throughout and operated in like manner as before described.

The two valves are of course intended to be closed and opened simultaneously to cut off or admit the gas.

I am aware that it is not, broadly speaking, new to embody in a valve of the character above mentioned the combination of the cap and the adjustable gland bolted to the cap, whereby the valve may be adjusted, and I therefore disclaim such combination, the invention claimed in my seventh claim being intended to be restricted to the combination of all of the particular elements therein mentioned, or their mechanical equivalents.

I do not desire to claim the use of a separate ring with internal water-circulation as a valve-seat; nor do I claim, broadly, a double valve,

since these features of construction are not new.

What I claim as my invention, and desire to secure by Letters Patent, is—

- 5 1. In a valve-body, the combination of the wrought-iron casing *a*, the annular flanged top and bottom pieces, *c d*, respectively, and the flanged ring *b*, mounted upon said bottom piece, said elements being arranged substantially as set forth.
2. The combination, with a pair of slide-valves arranged consecutively in a continuous passage, of an intermediate escape-orifice and a closing-door applied thereto in such manner as to open under light pressure, substantially as and for the purposes set forth.
3. The combination, with the valve-body, of the nozzle *k*, the cap *j*, and the hinge *l* intermediate between said nozzle and cap.
- 20 4. A hollow slide-valve adapted to move in horizontal bearings, and having the internal surfaces of its back and face inclined, so as to converge toward the point farthest from the stem, in combination with an inlet-pipe for water, and a hollow stem whose internal diameter is equal to the greatest vertical height of the interior of said valve-disk, whereby the trapping of steam within said disk is prevented, substantially as set forth.
- 25 5. The combination, with the hollow cylindrical valve-stem *s*, having an internal water-
- supply pipe, *t*, of the teeth *v v*, the periphery of whose ends coincides with that of the stem, the packing-ring *n'*, whose width is not less than the distance between two teeth, and the 35 pinion *w*, engaging with said teeth, the whole arranged and operating substantially as set forth.
6. The combination, with the valve-disk, of the hollow shield *s'*, applied around the end 40 thereof and projecting beyond the valve proper, substantially as and for the purposes set forth.
7. The combination, with the valve-stem, of the gland *r'*, having a sleeve, *u*, which is of less 45 diameter than the opening in the cap, and having laterally-projecting eyes *l'*, the screw-studs *i'*, whereby said gland is secured to the cap, the stems of said studs being of much smaller diameter than said eyes, and the inclined set-screws *m'*, bearing upon said studs, whereby the adjustment of the gland is effected, substantially as set forth.
8. The combination, with the gland, of the packing-ring *n'*, constructed in lapping segments, and the radial set-screws *o'*, arranged to bear upon said segments, substantially as set forth.
